UNITED STATES PATENT OFFICE.

ANTHONY HEINER, OF NEW YORK, N. Y.

COLOR PRESS.

Application filed May 8, 1925. Serial No. 28,954.

This invention relates to color presses, an object of the invention being to provide means whereby two or more colors are printed simultaneously.

Heretofore it has been necessary in color presses to run the paper through the press for each color whereas with my improved apparatus I print both colors simultaneously, thus resulting in a great saving of time and labor and also giving absolutely perfect results in the registry of the different colors.

My invention also includes improved means for inking the type beds for a transfer of a plurality of colors to the proper type beds, improved ink distribution, and other details of construction, all of which will more fully hereinafter appear in the specification and set forth in the claims.

With these and other objects in view, the invention consists in certain novel features of construction and combinations and arrangements of parts, which will be more fully hereinafter described and pointed out in the claims.

In the accompanying drawings—

Figure 1 is a view in side elevation of my improved press;

Figure 2 is a top plan view;

Figure 3 is a view in longitudinal section through the center of the press;

Figure 4 is an enlarged view in side elevation illustrating the inking mechanism;

Figure 5 is an enlarged view in longitudinal section through the center of the inking mechanism;

Figure 6 is a sectional plan view taken on the line 6—6 of Figure 5;

Figure 7 is a sectional plan view on the line 7—7 of Figure 5;

Figure 8 is a fragmentary view in vertical longitudinal section, showing the inking rolls in one position;

Figure 9 is a sectional plan view on the line 9—9 of Figure 8;

Figure 10 is a fragmentary view in end elevation looking at the upper end of Figure 6;

Figures 11 and 12 are fragmentary views in vertical longitudinal section, showing different positions of the inking rolls in applying the ink to the type beds;

Figure 13 is a fragmentary plan view on the line 13—13 of Figure 12;

Figure 14 is a fragmentary view in ver-

tical section at one end of one of the inking rolls and its adjacent parts, the view being taken on the line 14—14 of Figure 12.

1 represents the frame of my improved printing press which supports a drive shaft 2, on which latter a sprocket wheel 3 is fixed. An endless chain 4 connects the sprocket wheel 3 with a sprocket wheel 5 on a shaft 6. One run of the sprocket chain 4 engages and transmits motion to a sprocket wheel 7 on a shaft 8, as clearly shown in Figure 1.

9 represents a strip of paper which is fed from a suitable supply roll 10 through a guide and tensioning device 11, said paper having an intermittent positive movement which is caused by a pair of rolls 12 and 13. The roll 13 constitutes the driving roll, on the trunnion of which a gear wheel 14 is mounted and meshes with a rack 16. This gear wheel has a ratchet connection with the trunnion of the roll 13 so that it imparts motion in one direction only.

The rack 16 is movable in a guide 17 and is connected by a link 18 with a crank arm 19 fixed to shaft 6. This arm 19 has a longitudinal slot 20 therein, and a connecting bolt 21 projects through the link 18 and through the slot 20 and is secured by a set nut 22 so as to regulate the stroke or movement of the rack and the corresponding feed of the paper at each complete revolution of the shaft 6.

A transverse cutter 23 is provided at the end of the frame 1 to sever the paper transversely, and disk cutters 24 mounted on shafts 25 and 26, respectively, are adapted to sever the paper strip longitudinally so that by the operation of these cutters cards or sheets of the desired size can be automatically cut.

The transverse cutter 23 is provided with one or more depending rods 26 with springs 27 normally holding the cutter in elevated position. The lower ends of the rods 26 are connected by links 28 with a fixed part of the frame 1, and a controlling member 30 has a cam face 31 adapted to engage a cross member 33 which connects the links 28 and rods 26 so as to cause a downward movement of the cutter, as will be readily understood.

This operating member 30 is connected by a link 34 with a crank arm 35 on shaft 2, so that as the said shaft 2 revolves a reciprocating motion will be imparted to the

member 30. This member 30 has a suitable support or guide 36 and controls the vertical movement of my improved printing head 37. This head 37 is provided with a depending 5 yoke-like frame 38 carrying rollers 39 engaging the upper and lower faces of member 30.

Below the head 37 a platen 40 is provided, over which the paper strip 9 is fed. In this 10 head 37 I provide a plurality of type beds 41 and 42 located one in advance of the other but in the same horizontal plane, and while I have shown and shall describe two of these 15 type beds it is obvious that I may employ any desired number.

In the employment of the term "type bed" I use it in its broadest sense to include any form which may print or impress a color either in type or other character or form 20 upon the paper sheet 9.

43 represents a carriage which is secured to an upright 44 on operating member 30 and caused to reciprocate therewith. This carriage 43 supports the desired number of inking rolls. I have shown four inking rolls, 25 one pair of inking rolls 44 adapted to ink the bed 41 and another pair of inking rolls 45 adapted to ink the bed 42.

These pairs of inking rolls 44 and 45 are 30 supplied by ink of the desired color from fonts 46 and 47, respectively, which are shown in detail in Figures 4, 5 and 6, and will now be more specifically set forth.

The fonts 46 and 47 are located at the 35 upper portion of a frame 48 and have discharge rolls 49 which are engaged by rolls 50 connected by links 51. These rolls 50 also are adapted to engage supply rolls 52 and transfer ink from the rolls 49 to said rolls 52.

40 The rolls 50 are moved laterally when the link 51 is reciprocated by the movement of the rocker arms 57, as will be herein-after explained, and during such movement will take ink from the rolls 49 and deposit

45 it on the rolls 52, the two positions of these rolls 50 being illustrated in Figures 3 and 5, respectively. Rotary motion is applied to the rolls 52 through the medium of a sprocket chain 53 which connects the sprocket wheel

50 7, above referred to, with a sprocket wheel 54 on the trunnion of one of the rolls 52. The trunnions of these rolls 52 are connected by a gear train 55 so that they are 55 compelled to turn simultaneously in the same direction.

The links 51 above referred to are pivotally connected as shown at 56 to the rocker arms 57, the latter pivotally connected at 60 their lower ends to the frame 48 as shown at 58. The upper ends of these rocker arms 57 are connected to links 59, and one of the links 59 is connected to the upper end of a lever 60, the latter pivotally supported between its ends on the frame 48 as shown at 61.

A coil spring 62 connects the lever 60 with the frame 48 and tends to move the lever in one direction, while a cam 63 on shaft 6 positively moves the lever in the opposite direction. A pair of rocker arms 65 70 is connected to the link 59 and pivotally mounted upon the trunnions of the font rolls 49. These arms 65 carry pawls 66 which engage ratchet wheels 67 fixed to turn with the font rolls 49 so as to impart a partial 75 turning movement to said rolls at each movement of the lever 60.

At one side of the frame 48 a horizontal cross bar 68 is located and has forked ends 69 engaging grooved enlargements 70 on the ends of parallel rods 80. This construction is illustrated more clearly in Figures 6 and 10. The rods 80 are also mounted in suitable adjustable blocks 81 movable in the frame 48 and having set screws 82 to adjust the blocks.

The rods 80 carry distributing rolls 83 which engage the rolls 52, and rotary motion is imparted to these distributing rolls by their contact with the inking rolls. To impart a reciprocating movement to said distributing rolls 83 I provide cams 84 on the trunnions 85 of the rolls 52. These cams 84 engage rollers 86 on the bar 68, tending to move the bar in one direction, and a coil spring 87 located around a post 88 fixed to the frame 48 tends to move said bar 68 in the opposite direction. Hence, as the inking rolls 52 are revolved the distributing rolls 83 are caused to revolve and to reciprocate and smear the ink smoothly over the rolls 52.

To return to the inking rolls 44 and 45 and their operating and controlling mechanism, attention is particularly called to Figures 3, 7, 8, 9, 11, 12, 13 and 14. Each of these inking rolls is mounted alike at both ends, and in Figure 14 I show how one end of one of these rolls is mounted, it being understood that this applies to both ends and all of the rolls 44 and 45.

Each of these rolls has trunnions 89 at both ends and each trunnion is mounted in a sliding block 90 movable in a vertical slot 91 in the carrier 43. Each block 90 has a roller 92 mounted thereon and a coil spring 93 in the upper portion of the carrier 43 exerts downward pressure on the block 90, tending to move the roll downwardly.

All of the rolls 44 and 45 therefore have supporting rollers 92 at both ends and these supporting rollers are adapted to engage cams which elevate the rollers at the proper time and during the proper length of time in accordance with the movement of the carrier 43, all of which will now be explained in detail.

In a plane below the ink supply rollers 52 two pairs of cams 93 and 94 are located. The rollers 92 of the inking rolls 45 ride up the cam 94, and the rollers 92 of the rolls

44 ride up the cam 93 so that said rolls are presented to contact with the rolls 52 and so that the rolls 45 always take ink from the right-hand roll 52 while the rolls 44 always 5 take ink from the left-hand roll 52 in Figure 5.

It is to be assumed, of course, that the ink on the two rolls 52 are of different colors. The rolls 45 can never contact with the left-hand rolls 52 as they move downwardly off the cams 94 in their movement to the left of Figure 5.

As these rollers 44 and 45 move under the head 37, cams 95 and 96, respectively, cause 15 the rolls to engage with their proper type beds 41 and 42. In other words, the cams 95 elevate the rolls 44 so that they engage the type bed 41 while the cams 96 elevate the rolls 45 so that they engage the type bed 20 42.

It will thus be seen that ink of one color is applied to the type bed 41 and ink of another color to the type bed 42, and that the rollers 44 never engage the type bed 42 and 25 the rollers 45 never engage the type bed 41 because of the location and arrangement of the cams 95 and 96.

The operation in general is as follows:

With the parts shown in the position illustrated in Figures 1, 2 and 3 the operating member 30 is in an extreme position. As the shaft 2 revolves this member 30 is moved to the right of Figure 3 and carries the rollers 45 and 44 under the head 37. The 30 cams 93 and 94 elevate the rollers 45 into engagement with the type bed 42, and the cams 95 and 96 elevate the rollers 44 into contact with the type bed 41. As these rollers move up their respective type beds they 35 drop down off their elevating cams and continue to move to the right until they are elevated by the respective cams 93 and 94 into contact with the ink supply rolls 52 and take a new supply of ink for their return movement. During this movement to the right of Figure 3 the member 30 by 40 reason of its cam face 31 causes the type head 37 to descend and bring the type beds into engagement with the strip of paper 9. In the movement to the left of Figure 3 the head 37 is again elevated and the paper is caused to move a proper distance by the 45 rack 16 and pinion 14, as above explained. During the longitudinal movement of the 50 paper the cutters 24 sever the same longitudinally and at each reciprocation of the 55

member 30 the cutter 23 is operated to sever the paper strip 9 transversely.

It will thus be noted that with my improved apparatus I apply to the upper strip two colors simultaneously, the second color being applied to the same space or spaces upon the next operation of the printing head, so that the plurality of colors are always in register and the work is done continuously, dispensing with the necessity for running the paper twice through the press, such as is the common practice.

Various slight changes and alterations might be made in the general form of the 70 parts described without departing from my invention, and hence I do not limit myself to the precise details set forth but consider myself at liberty to make such slight changes and alterations as fairly fall within the 75 spirit and scope of the appended claims.

I claim:

1. A color press, including a platen, a vertically movable head, a plurality of type beds located in the same horizontal plane at 80 the lower portion of the head, a plurality of inking fonts containing inks of different colors, a plurality of inking rolls movable horizontally and longitudinally of the press from the fonts to the type beds, cams causing the elevation of certain of said last-mentioned rolls into contact with certain of the fonts, and other means causing the elevation of certain of said rolls into contact with certain of the type beds whereby ink 85 of one color is imparted to one type bed and ink of another color to the other type bed.

2. A color press, including a platen, a vertically movable head, a plurality of type beds located in the same horizontal plane at 90 the lower portion of the head, a plurality of inking fonts of different colors, a plurality of inking rolls movable horizontally and longitudinally of the press from the fonts to the type beds, cams causing the elevation of certain of said last-mentioned rolls into contact with certain of the fonts, other means causing the elevation of certain of said rolls into contact with certain of the type beds whereby ink of one color is imparted to one type bed and ink of another color to the other type bed, and means for moving a strip of paper between the platen and the head a distance equal to the distance 100 between the type beds at each movement of the head.

ANTHONY HEINER.
